H. S. KRATZ.
Stove-Pipe Shelf.

No. 223,150.

Patented Dec. 30, 1879.

UNITED STATES PATENT OFFICE.

HENRY S. KRATZ, OF CHICAGO, ILLINOIS.

IMPROVEMENT IN STOVE-PIPE SHELVES.

Specification forming part of Letters Patent No. **223,150**, dated December 30, 1879; application filed June 20, 1879.

To all whom it may concern:

Be it known that I, HENRY S. KRATZ, of Chicago, in the county of Cook and State of Illinois, have invented a new and Improved Stove-Pipe Shelf; and I do hereby declare that the following is a full, clear, and exact description of the same.

The object of my invention is to provide an improved shelf for attachment to stove-pipes for the purpose of supporting culinary vessels, dishes, clothes, or other things requiring to be kept warm or dried.

The invention consists in the construction and combination of parts as hereinafter described and claimed.

In the accompanying drawings forming part of this specification, Figure 1 is a plan view of the pipe shelf or collar, with a shelf proper and towel-rack attached. Fig. 2 is a longitudinal vertical section of the shelf on line *xx*, Fig. 1, showing also two of its detachable appendages in the inclined or vertical position they assume when not in use. Fig. 3 is a side view of the pipe shelf or collar having a dish-shelf suspended in vertical position. Fig. 4 is a detail section on line *yy*, Fig. 1.

The bracket or collar is constructed in two parts, *A A*, whose inner sides have a semicircular shape, so that when placed together they will fit closely around the body of a stove-pipe which has the required diameter.

The parts *A A* are secured together and clamped firmly around the stove-pipe, so as to be self-supporting, at any desired height from the stove by means of bolts or screws *C*, which pass through the lugs *b* that project laterally from the ends of the parts *A A*, and are perforated transversely, as shown.

Each part *A* of the bracket has two horizontal flanges, *d e*. The flange *d* projects in a different vertical plane from the other, *e*, and is also narrower. The lower flanges, *e e*, are separated from the body *A* of the collar for a portion of their length, thus forming openings *f*, and they are of such form that the outline of the bracket as a whole is approximately that of an oblong rectangle. Each rounded corner of the lower flange, *e*, has a series of holes,

g, and the upper flange, *d*, has a socket, *h*, in its under side.

The open-work or skeleton shelves *D* have upwardly-projecting pintles *i* on their inner ends, Fig. 4. When the shelves are placed in horizontal position, as shown in Figs. 1 and 4, for supporting dishes or other articles, these pintles *i* enter the sockets *h*, and thus prevent accidental detachment of the shelves. The support of the latter in such position is obviously due to the leverage between the flanges *d* and *e*, there being a downward pressure upon flange *e* and an upward pressure against flange *d*.

Four shelves, *D*, may be supported by the bracket at the same time, one being placed at each corner thereof; but in practice I design the set to be furnished to purchasers with three shelves and one towel-rack or clothes-bar holder *E*. The latter consists of a triangular plate having sockets for reception of radiating bars for supporting clothes.

When the shelves and clothes-bar holder are not in use they may be changed to the position shown in Figs. 2 and 3, so as to occupy less space radially to the collar *A*. In such case the shelves *D* are supported vertically by means of their central points, *l*, which enter the holes *g* in the angle of the lower flange, *e*, while the holder *E* is inserted in one of the openings *f* between the flanges.

I do not claim a stove-pipe collar having two parallel horizontal flanges for supporting detachable shelves; nor do I claim, broadly, providing one of such flanges with a recess to receive a stud fixed to the shelf; but

What I claim is—

The combination of the collar having the flange *e*, provided with holes, as specified, and the shelves *D*, having the central openings and provided with the points *l*, as shown and described, whereby said shelves are adapted to be attached to and supported vertically on said collar-flange when not required for use.

HENRY STOVER KRATZ.
